(57) **CLAIM**

The ornamental design for an “open reed game call apparatus,” as shown and described.

DESCRIPTION

FIG. 1 is a perspective view of an open reed game call apparatus according to the present invention;

FIG. 2 is a top view thereof;

FIG. 3 is an inverted left side elevation view thereof;

FIG. 4 is a bottom view thereof;

FIG. 5 is a right side elevation view thereof;

FIG. 6 is a rear elevation view thereof; and,

FIG. 7 is a front elevation view thereof.
